CLAIM

The ornamental design for a cup lid, as shown and described.

DESCRIPTION

FIG. 1 is a front elevational view of a cup lid showing our new design.

FIG. 2 is a rear elevational view of the cup lid shown in FIG. 1.

FIG. 3 is a right elevational view of the cup lid shown in FIG. 1.

FIG. 4 is a left elevational view of the cup lid shown in FIG. 1.

FIG. 5 is a top elevational view of the cup lid shown in FIG. 1.

FIG. 6 is a bottom elevational view of the cup lid shown in FIG. 1.

FIG. 7 is a perspective view of a front side of the cup lid shown in FIG. 1.

FIG. 8 is another perspective view of the front side of the cup lid shown in FIG. 1.

FIG. 9 is a perspective view of a rear side of the cup lid shown in FIG. 1; and,

FIG. 10 is a cross-sectional view thereof, taken along line 10-10 of FIG. 1.

1 Claim, 5 Drawing Sheets
